UNITED STATES PATENT OFFICE

HERMAN F. COORS, OF LOS ANGELES, CALIFORNIA, ASSIGNOR TO H. F. COORS COMPANY, INC., OF INGLEWOOD, CALIFORNIA, A CORPORATION OF CALIFORNIA

METHOD OF FORMING SECURING MEANS ON THE RIMS OF JARS

Application filed October 15, 1927. Serial No. 226,297.

This invention relates to a jar, and is more particularly related to a jar and method of and means for securing a cap thereto, and is particularly related to jars formed of clay, glass, and the like.

The securing of caps to jars, particularly those formed of clay or glass, is difficult and the means heretofore provided for securing caps to jars of this class have for the most part included the forming on the rim of the jar threads or thread segments by means of which the cap is held in place through lugs or the like formed on the lower ends of said cap. These lugs or threads are easily broken off of the rims, permitting the caps to leak and these lugs or threads are also unsatisfactory in that they do not permanently provide means by which the cap may be secured to the rim of the jar in a manner to provide a fluid-tight seal between the jar and the cap but the threads often have flat places in which the lugs seat which are not the proper seats for the lugs in order to insure a fluid-tight connection between the cap and the rim of the jar. In the forming of jars of clay, it is necessary to position the threads or thread segments on the rim of the jar in a separate operation and to then burn the jar with the thread segments thereon, which results in the contraction of the material of which the thread sections are formed and it is also practically impossible to form accurate threads by this method.

It is, therefore, an object of this invention to provide a method of forming securing means on the rim of a jar by means of which a cap may be secured to the jar in a permanent and fluid-tight manner, and which securing means may be formed during the formation of the jar.

Another object of this invention is to provide a method of forming means for securing a cap having a plurality of lugs to the rim of a jar, which includes the forming of vertically extending recesses in the rim of the jar and cutting out in the rim of the jar, by means of a tool, a lug slot which communicates with the vertically extending recesses and into which the lugs of the cap are adapt-

ed to be rotated from the recess in order to hold the cap permanently in position.

Another object of this invention is to provide a jar including at its upper end a rim having vertically extending recesses formed therein and inclined slots formed with one end communicating with said recesses into which lugs formed on a cap are adapted to fit to hold the cap in fluid-tight relation with said rim.

Another object of this invention is to provide means adapted to be employed in the forming of a rim of a jar with vertically extending recesses and inclined slots communicating with said recesses.

Other objects and advantages of this invention, it is believed, will be apparent from the following detailed description of a preferred embodiment thereof, as illustrated in the accompanying drawings.

In the drawings:

Figure 1 is an exploded perspective view of a cap and jar formed in accordance with this invention.

Figure 2 is a similar exploded perspective view illustrating the jar and rim thereof with the rim formed with slots therein and also illustrating the means for forming the vertically extending recesses and slots as embodied in this invention.

Figure 3 is a side elevation of a jar illustrating the means for carrying out the method embodying this invention as positioned upon the rim of the jar.

Figure 4 is a sectional end elevation taken substantially on the line 4—4 of Figure 3.

Figure 5 is a perspective view of the slot forming tool embodied in this invention.

The method embodying this invention includes first the formation of a jar 1 of clay, glass, or like material, having a rim 2 formed integral therewith. A die ring 3 having guide blocks 4 on its inner periphery is then slid over the rim 2, the guide blocks 4 acting to center the ring 3 on the rim 2 vertically by passing into vertically extending recesses 5 formed at spaced points around the periphery of the rim 2 during the molding or blowing of the jar. The die ring 3 has formed around its periphery a plurality of inclined

slots 6 which extend into the guide blocks 4, as illustrated at 7. After the die ring 3 has been mounted on the rim 2, forming the recesses 5, the cutter 8 is inserted in the slots 6 to form from the recesses 5 inclined ways 5 or slots 9 into which the lugs 10 of the cap 11 are adapted to pass after the cap has been mounted on the rim 2 so that the lugs 10 pass downwardly through the recesses 5 until they 10 are engaged in the ways 9. The cap 11 is then rotated and the rotation of the cap 11 with the lugs 10 in the ways 9 causes the cap 11 to be drawn downwardly on the rim 2 to form a fluid-tight connection between the rim 2 and cap 11 by means of a washer of resilient material which is customarily provided between such a cap 11 and rim 2.

The cutter tool 8 is formed of a shank 12 to which a handle 13 is secured. The end of the shank 12 is curved to provide a loop cutter 14 which is fitted into the slots 6 in order to form the ways 9 and is also bent to form a stop section 15 which engages the edge of the die 3 in order to determine the depth to which 25 the ways 9 are formed in the ring 2 of the jar or bottle 1.

In case this method is employed on jars formed of clay, the recesses 5 and inclined ways are formed in the ring 2 prior to the drying and burning of the clay, and in case this method and means are employed in forming the securing means for a cap embodying this invention in a glass jar, it is believed that it would be advisable to employ 35 the die on the rim of the jar after the glass has been blown and employing in the die 3 cutters preferably of the diamond type and similar to the tool 8 but having a diamond cutter carried on its end to form the ways 9. It is also possible to form the jar embodying 40 this invention of glass by blowing glass into a mold having means for forming the vertically extending recesses 5 and the inclined ways 9 during the blowing of the jar.

Having fully described my invention, it is to be understood that I do not wish to be limited to the details herein set forth, which may obviously be varied without departing 50 from the spirit of my invention as defined in the appended claims.

I claim:

1. The method of forming securing means on a jar for a cover including the forming of vertically extending recesses in the rim of the jar, and cutting out inclined ways in the rim of said jar communicating with said recesses.

2. A method of forming jars having cover securing means including the molding of the jar, forming vertically extending ways in the rim of the jar, and cutting out inclined slots in the rim of said jar from said recesses.

3. The method of forming a jar of clay or the like, including molding the jar with a 65 rim, forming vertically extending slots in

said rim, and inclined ways from said slots prior to the drying of said clay.

4. The method of forming securing means on the rim of a jar including the forming of vertically extending recesses in the rim of the jar, mounting a die ring on the rim, inserting a cutting tool in slots formed in the guide ring, and moving said cutting tool longitudinally in said slot to form inclined slots in the rim of said jar from said recesses.

5. The method of forming securing means on the rim of a jar or a cover including the forming of a plurality of diametrically opposed vertically extending recesses in the rim of the jar, fitting a die ring on the rim of the jar with lugs extending into said recesses, inserting a cutting tool in guide slots formed in the die ring, and moving the cutting tool in the guide slots to form inclined ways in the rim of the jar to extend downwardly from the said recesses.

Signed at Los Angeles, California, this 5 day of October, 1927.
